TELESCOPIC UMBRELLA

Filed Aug. 16, 1930

Inventor:

Hans Haupt.

UNITED STATES PATENT OFFICE

HANS HAUPT, OF BERLIN, GERMANY

TELESCOPIC UMBRELLA

Application filed August 16, 1930, Serial No. 475,647, and in Germany July 19, 1930.

This invention relates to a collapsible umbrella of the kind wherein the stretchers are pivoted to the outer rib sections and supported by auxiliary struts, and the invention consists essentially in connecting the upper ends 5 of the struts to a sleeve which is arranged to slide on the telescopic umbrella stick.

This arrangement has the advantage that, as the sleeve moves over the stick sections 10 and the catches therefor, a resistance will be offered to the sleeve which re-acts by means of the struts on the stretchers so as to extend the outer rib sections before the ribs are bent enough to hinder such extension.

15 This effect is enhanced by making the uppermost stick section larger than the contiguous lower section so that it can act frictionally on the sleeve.

Fig. 1 of the accompanying drawing represents a side view, partly in section, of the improved umbrella frame in closed position, only one of the ribs and its accompanying parts being shown, and

20 Fig. 2 is a sectional view of the lower part of the frame in collapsed position.

The umbrella comprises rib sections 1 and 2 which are slidably connected to each other by means of rings 3 and 4, the sections 1 being pivoted to the crown 5. The stretchers 6 are connected by joints 7 to the rings 4 of the outer rib sections 2. The stick is composed of telescopic sections 8, 9, 10 and 11 which are locked by catches 12, 13 and 14 preventing longitudinal relative displacement.

30 Connected to the lower end of the stick section 8 is a tubular handle 17. The latter can, after the catch 12 has been depressed, slide over the runner 18 between the stretchers 6 and the ribs 2 while the stick section 8 slides over and depresses the catches

35 13 and 14 so as to allow the upper stick sections to collapse. The runner is locked by the catch 14 with the umbrella frame in open position. Connected to each stretcher by means 40 of a joint 19 is an auxiliary strut 20 which, when the umbrella is opened, supports the stretcher and helps it to extend the outer rib section 2.

In the closed position of the umbrella 45 frame, the runner 18 is locked by a catch 23

provided, under the runner, with a nose 24 whereby the catch can be operated for releasing the runner. On the collapse of the umbrella frame the runner slides over the nose 24 and moves to the bottom of the handle, as 55 shown in Fig. 2, and the catch 23 remains in position to re-engage the runner and ensure a simultaneous extension of stick and ribs.

The auxiliary struts are made of springy material and are formed with knees 26 whereby they, on the closing of the umbrella, engage the stretchers 6 and exert thereon an outward thrust whereby the re-opening of the umbrella is facilitated.

While the auxiliary struts 20 are connected at one end, by means of the joints 19, to the stretcher 6 the other end is connected to a sleeve 27 which slides on the stick. This sleeve is freely slidable. However, since it is connected to the auxiliary struts, it can only 60 move together with all the latter. Thus, on the handle 7 being pushed over the stretchers 6, the sleeve and struts co-operate to support the stretchers. The joints 19 of the struts 20 are arranged on the stretchers 6 outside 65 the position to which the handle can be pushed. Thus the handle is prevented from acting with too great force on the joints 7 so as to hinder the relative sliding movement of the rib sections.

70 Fig. 2 shows the lower part of the frame in collapsed position. The stick section 11 over which the slide 27 passes on the opening of the umbrella is larger than the contiguous lower section is adapted to resist the movement of the slide, thereby reacting by means of the struts on 75 the stretchers 6 so as to extend the outer rib sections 2 before the ribs are bent enough to hinder such extension.

The runner 18 is adapted to move on to the sleeve 27 on the opening of the umbrella. On 80 the closing of the umbrella the sleeve 27 will not be retained by the catch 14 since it moves on to the catch while the latter is depressed by the runner. When the umbrella is opened, the catch 14 acts as an initial resistance to 85 the sleeve 27, thereby assisting the struts and the stretchers in extending the outer rib sections.

I claim:

1. An umbrella of the character described, 100

- comprising a stick composed of telescopically connected sections, ribs composed of slidably connected sections, a runner on the stick, stretchers connecting said runners with the
5 outer rib sections, a sleeve arranged to slide on the stick, and auxiliary struts pivoted at one end to said sleeve and at the other end to the central portions of the stretchers for supporting the latter in the open position of
10 the umbrella, said struts being formed with knees adapted to bear against and exert outward pressure on the stretchers when the umbrella is closed.
2. An umbrella as claimed in claim 1 where-
15 in the uppermost stick section is larger than the contiguous lower section and is adapted to offer frictional resistance to the sleeve, sub-stantially as and for the purpose set forth.
3. An umbrella as claimed in claim 1
20 wherein the uppermost stick section is larger than the contiguous lower section, a catch on said lower section adapted to retain the uppermost section in extended position, said catch adapted to offer frictional resistance to
25 the upward movement of the sleeve on the latter passing the catch substantially as and for the purpose set forth.

HANS HAUPT.
